PYROLYSIS OF HYDROCARBON FLUIDS

Hermann C. Schutt, North Tarrytown, N. Y., assignor to The Pure Oil Company, Chicago, Ill., a corporation of Ohio

Application July 24, 1937, Serial No. 155,517

5 Claims. (Cl. 196—10)

This invention relates to improvements in the thermolytic conversion of hydrocarbon fluids and is more particularly concerned with improvements in thermal polymerization of olefinic gases to hydrocarbons boiling within the gasoline range.

In the conversion of hydrocarbon fluids by strictly pyrolytic processes, it is necessary to use such high temperatures that conversion will proceed too far or secondary reactions will occur unless the reaction is suddenly halted. It has become common practice among refiners to employ shock chilling for that purpose. A cool oil fraction is directly contacted with the reaction products immediately upon their emergence from the reaction zone and the temperature of the reaction products thereby suddenly reduced to a point where reaction ceases. As chilling stock, it is preferable to use a condensate rather than residual stock for the reason that the latter deposits carbon at the point of chilling and is, therefore, objectionable.

However, if the temperature of the reaction products, during chilling, is lowered only to a point such that the chilled products can be fractionated without further heating, the chilled products have a marked tendency to deposit carbon in the transfer line between the chiller and the fractionator or separator.

The object of this invention is to provide method and apparatus to overcome the clogging and coking of the transfer line from the chiller or arrester to the separator or fractionator.

It has been found that if the reaction products from a conversion zone are chilled by means of cool condensate to a temperature below that of conversion, for example, approximately 600° F., and a stream of hot residual oil is injected into the stream of reaction products immediately after cooling below conversion temperature, the residual oil will act as a solvent and carrying agent for the tarry matter and coke, thereby preventing deposition thereof in the transfer line and making possible much longer runs.

In order to better understand the invention, reference should be had to the following description together with the accompanying drawing of which

The single figure is a diagrammatic side elevational view of apparatus suitable for carrying out the invention.

Although the invention will be described in connection with the polymerization of hydrocarbon gas consisting chiefly of C₃ and C₄ fractions, a large portion of which is olefinic, it is

to be understood that the invention is not limited to treatment of that type of gas but covers treatment of hydrocarbon gases in general.

Referring to the drawing, the numeral 1 indicates a line through which gas is charged to the system. This gas is preferably a gas from the stabilizer of an oil cracking unit and may be composed chiefly of C₃ and C₄ hydrocarbons with a small amount of C₂ hydrocarbons. The gas may be charged under pressure of approximately 50–200 pounds per square inch. The gas is cooled during passage through cooling coil 3 from which it passes into feed tank 5. In the tank 5 the gases may be in substantially liquid condition or in a condition of mixed gas and liquid, depending upon the composition of the gas and the conditions of pressure and temperature maintained. The gas is taken from the feed tank 5 through line 7 by means of pump or compressor 9 in which the gas is raised to the desired pressure which may be from 200–5000 or more pounds per square inch. The compressed gas, which is substantially in the liquid state, is charged through heat exchanger 11 wherein it may pass in indirect heat exchange with hot condensate and may be preheated to a temperature of approximately 200°–400° F. The preheated gas leaves the exchanger through line 13 and passes into the inlet of heating coil 15 located in furnace 17.

In the heating coil the gases are heated, while maintained under the aforesaid pressure, to temperatures ranging from 800°–1200° F., depending upon the pressure, the composition of the charge, and upon the product desired. If high pressures are employed, the temperature will not be substantially in excess of 1050° F.; if low pressures of the order of 200 pounds per square inch are employed, the temperature will preferably be from 1075°–1200° F. In the latter case the resulting liquid product will be predominantly aromatic. Of course, if the charge to the heating coil is predominantly or entirely saturated, it may be desirable to use lower pressures than those above mentioned and higher temperatures in order to crack the gases to produce olefins.

From the heating coil 15 the heated gases pass to reaction coil 18 wherein the products are maintained under substantially the same temperature and pressure existing in the heating coil, for a period of time sufficient to bring about conversion of a substantial portion of the gases to liquid hydrocarbons. The reaction coil is preferably of larger cross-sectional area than the heating coil and may take the form of a cham-

ber. The reaction coil is also preferably enclosed in a suitable housing which will permit controlled passage therethrough of a cooling fluid, such as air or flue gas, in order to prevent undue rise of temperature.

The reaction products upon leaving the reaction coil are immediately and suddenly chilled to a temperature below that at which conversion takes place, by injecting into the stream at the point 19, cool condensate. The temperature is preferably lowered to approximately 600° F. It is not desirable to chill the reaction products to temperatures materially below 600° F. since to do so would necessitate subsequent heating of the products before fractionation thereof. At a temperature of about 600° F. the reaction products can be fractionated into the desired cuts without additional heat. The chilled products pass through transfer line 21 to the point 23, a short distance from the point 19, and at the point 23 hot residual oil is injected into the partially cooled stream of reaction products. The residual oil is injected at a temperature not materially below the temperature of the chilled products. In commercial operation the residual oil may be at a temperature of from 525°-575° F. The residual oil acts as a solvent or carrying agent for the tarry and coky constituents present in the reaction products and prevents deposition of these materials in the transfer line. The combined products then pass through valve 25 into the lower portion of the fractionating tower 27. At the valve 25, pressure may be reduced so that the pressure in the fractionating tower will be maintained between approximately 175-250 pounds per square inch.

Vaporization and fractionation of the products take place in the tower 27. A condensate heavier than gasoline and corresponding substantially to gas oil is collected on the plate 29. The gasoline boiling constituents are condensed in the fractionating tower and collected on the plate 31. Uncondensed gases and vapors leave the top of the tower through the line 33 controlled by valve 35, where the pressure is reduced to substantially atmospheric, then pass through cooling and condensing coil 37, into gas and liquid separator 39. Any condensate in the separator 39 is withdrawn therefrom through line 41 by means of pump 43 and recycled to the top of the fractionator as reflux liquid.

The gasoline fraction is withdrawn from the fractionator through line 45 controlled by valve 47 and passed into stripper 49 which may be provided with suitable fractionating plates in order to separate the gasoline boiling constituents from those constituents lighter than gasoline and thereby stabilize the former. A portion of the liquid from the bottom of the stripper is continuously withdrawn through line 51, passed through heat exchanger or reboiler 53 where it is heated and recycled back to the stripper to a higher point in the stripper, through line 55. The stabilized end point gasoline is continuously withdrawn from the stripper through line 57 controlled by valve 58, to storage. The gases and vapors removed from the distillate in the stripper 49 are taken from the top thereof through line 59 and returned to the upper portion of the fractionator.

Intermediate condensate or condensate heavier than gasoline is withdrawn from the fractionator through line 61 by means of pump 63. The stream of condensate may be split into two parts —one part passing through line 64 controlled by

valve 65 and then through heat exchanger 11 wherein it is partially cooled by indirect contact with the cool gas charge. The partially cooled condensate leaves the heat exchanger 11, through line 66, is further cooled in the cooler 67 to a temperature of approximately 80°-100° F. and injected into the stream of reaction products at the point 19; the other portion of the condensate may be passed through line 69 controlled by valve 71 into exchanger or reboiler 53 where it imparts heat to the condensate from the stripper 49, leaves the reboiler 53 through line 72, passes through heat exchanger 73 through line 75, and joins the other portion of the condensate in line 66. If desired, part or all the condensate in line 72 may by-pass exchanger 73 by being passed through valve controlled line 75. It will be understood that all the condensate may be passed through one or the other of these two lines, or the condensate may be split in any proportion between the two.

Residual oil may be withdrawn from the fractionating tower at a point a short distance above the bottom thereof through line 76, by means of pump 77, and injected into the line 21 at the point 23. The remainder of the residual oil, with its content of tarry material and suspended carbon, may be withdrawn from the fractionator through line 79 and float controlled valve 81, and passed to storage.

Uncondensed gases from the gas-liquid separator 39 are withdrawn therefrom through line 83 by means of compressor 85 wherein the gases are compressed to a pressure between 150-1000 pounds per square inch, and then pass into the intermediate portion of fractionating tower 87. The portion of the gas which remains liquid gravitates to the bottom of the fractionating tower and may be withdrawn therefrom through line 89, then passed through heat exchanger 73 in order to heat the gases if necessary, and recycled through line 91 to the fractionator below the point of inlet of the compressed gas. The bottom of the fractionator is preferably maintained at a temperature of 90°-150° F. in order to insure that the liquid collected in the bottom of the fractionator is free from methane and hydrogen. The uncondensed gases leave the top of the fractionator and pass into an after-cooler 93 which is cooled by means of brine coil 95 or other refrigerating means in order to condense C₃ and C₄ hydrocarbons together with a portion of C₂ hydrocarbons. The temperature in the after-cooler 93 is regulated in accordance with the pressure maintained so that hydrogen and methane are not condensed. The latter gases, together with a portion of the C₂ hydrocarbons, leave the after-cooler through line 97 controlled by valve 99 and are eliminated from the system. The C₃ and C₄ hydrocarbons, together with a portion of the C₂ hydrocarbons in liquefied condition, are withdrawn from the bottom of the fractionator through line 101 controlled by valve 103 and fed to the feed tank 5 where they are mixed with the fresh gas for recycle to the process.

It will be seen, therefore, that by fractionating the reaction products into a condensate heavier than gasoline and residual oil, the heavy condensate can be cooled down low enough to suddenly chill the reaction products to fractionating temperature and the residual oil can immediately thereafter be injected into the transfer line without substantially lowering the temperature of

the chilled products and thereby prevent carbon deposition and clogging in the line.

What is claimed is:

1. In a process for converting hydrocarbon gases to hydrocarbons boiling within the gasoline range, at high temperatures, the steps of suddenly chilling the reaction products from such conversion process to a temperature not substantially in excess of 600° F. but not below a temperature at which the products are fractionated to obtain residual oil, heavy condensate and gasoline, by contacting the hot reaction products with cool condensate, adding residual oil of the type above fractionated to the partially cooled reaction products immediately following said chilling step to prevent deposition of tar and carbon, said residual oil being at a temperature which will not cause material change in temperature of the partially cooled products, and fractionating the mixture. 5
2. The steps in accordance with claim 1 in which the intermediate condensate and residual oil are produced in the process. 10
3. The steps in accordance with claim 1 in which the reaction products are chilled to approximately 600° F. and residual oil at a temperature of 525°-575° F. is added to the partially cooled products. 15
4. The process of polymerizing olefinic gases which comprises passing said gases through a reaction zone wherein they are subjected to temperatures between 800° and 1200° F. and pressures between 200 and 5000 pounds per square inch for a period of time sufficient to convert a substantial portion thereof to gasoline boiling range constituents, contacting the reaction products immediately upon emergence from the reaction zone with cool condensate subsequently 20
- separated from the reaction products in order to quench to a temperature not substantially in excess of 600° F. but not below a temperature at which separation of gasoline boiling constituents from heavier constituents can be effected, passing the quenched products through a conduit to a fractionating zone, separating the reaction products in said fractionating zone into residual oil, condensate heavier than gasoline and a gasoline boiling range fraction, and contacting said residual oil without cooling with the quenched reaction products during passage through said conduit and before release of pressure. 25
5. In a process for converting hydrocarbon gas to hydrocarbons boiling within the gasoline range, at high temperatures, the steps of suddenly chilling the reaction products from such conversion process to a temperature not substantially in excess of 600° F. but not below a fractionating temperature by contacting the hot reaction products with cool condensate, passing the chilled products through a conduit to a fractionating zone in order to separate the products into residual oil, condensate heavier than gasoline, gasoline distillate and gases lighter than gasoline, stabilizing the gasoline distillate in a separate zone, passing the condensate heavier than gasoline in indirect contact with said withdrawn gasoline distillate in order to heat said distillate sufficiently to stabilize it and to partially cool said condensate, 30 using said cooled condensate as the condensate for chilling the reaction products, and contacting said residual oil, without substantially cooling, with the chilled reaction products in said conduit immediately after cooling with said condensate. 35
